G. W. DE WATERS.
CASEMENT WINDOW STRUCTURE.
APPLICATION FILED JUNE 20, 1921.

1,436,951.

Patented Nov. 28, 1922.

UNITED STATES PATENT OFFICE.

GEORGIANNA W. DE WATERS, OF PITTSBURGH, PENNSYLVANIA.

CASEMENT-WINDOW STRUCTURE.

Application filed June 20, 1921. Serial No. 478,862.

To all whom it may concern:

Be it known that I, GEORGIANNA W. DE WATERS, a citizen of the United States, and residing in the city of Pittsburgh, in the 5 county of Allegheny and State of Pennsylvania, have invented or discovered the new, useful, and Improved Casement-Window Structures, of which the following is a specification.

10 My invention consists in certain new and useful improvements in casement windows.

The object which I have in view is a substantial yet inexpensive casement window structure wherein the window opens inwardly on a vertical axis; is rain-tight when closed, and is easy to operate in either opening or closing.

I accomplish this object by the provision of a structure presenting the following 20 characteristics. The window frame is provided with downwardly and outwardly inclined surfaces at its top and bottom and the top and bottom of the sash are provided with similar surfaces adapted to mate therewith, but the sash is sufficiently shorter than the opening in the frame to permit the window to be swung into its closed position at the proper elevation to mate its upper 25 surface with the upper incline surface of the frame while its lower edge clears the lower bar of the frame. The sash is then lowered and nested so that its lower edge mates with the lower incline surface of the frame. Means are provided for enclosing from 30 without the space between the upper edge of the sash and the top of the window opening when the window is closed, and also for sealing from without the vertical edges of the sash when closed. I also provide a novel 35 form of hinges which support the sash when open and which permit of raising the sash sufficiently, in closing, to permit it to clear the bottom bar of the frame, as above described.

40 Other novel features of construction and arrangement of parts will appear from the following description.

In the accompanying drawings, which are intended to illustrate the principles of my 50 invention, Fig. 1 is an elevation showing an inside view of the window frame and sash with the latter closed; Fig. 2 is a vertical section of the frame, the window being shown swung partly open; Fig. 3 is a broken 55 sectional view taken along the line III-III in Fig. 1; Fig. 4 is a horizontal section

taken along the line IV-IV in Fig. 3, and Fig. 5 is an enlarged detail showing the form of hinge used.

The following is a detailed description of 60 the drawings.

A represents the window frame, which is of course built into the building in the usual manner, and B represents the glazed sash which is hinged to the frame by one of its 65 vertical edges. The form of hinge which I show comprises the sash plate 1, the frame plate 2 and the pintle 3. The sash plate is provided with a single pintle sleeve which is interposed between the upper and lower 70 pintle sleeves of the frame plate, sufficient clearance being provided for the sash plate sleeve so that the sash may be raised and lowered on its hinges relative to the frame, as will later more clearly appear. 75

4 represents the handle or lever of a spring catch or lock mortised into the edge of the sash and adapted to engage a suitable keeper mortised into the frame in the usual manner. 80

I prefer to provide the bottom bar of the sash with a suitable grasp 5 to aid in raising the sash on its hinges, and to open and close the sash.

The top bar of the window frame has its 85 lower surface in the form of a downward and outward incline 6, while the upper bar of the sash has its upper surface in the form of a complementary incline 7 adapted to mate with incline 6. The bottom bar of the 90 window frame has its upper surface in the form of a downward and outward incline 8 and the bottom bar of the sash has its lower surface in a complementary incline 9 adapted to mate with the incline 8. The sash, 95 however, is sufficiently less in height than the opening in the window frame so that when closed the sash may be lifted vertically on its hinges so as to clear the bottom bar of the frame when opening, and when being 100 closed, may be lifted vertically until its upper incline 7 mates with the incline 6 of the frame, thereby clearing the bottom bar of the frame. When the sash has been elevated and then swung open, it is permitted 105 to drop until it is supported on its hinges, as shown in Fig. 2. When elevated and swung into its closed position, the sash is permitted to drop until it nests with the frame as shown in Figs. 1 and 3. When closed and 110 nested, there is a vacant space 10 at the top of the sash which is sealed from without by

means of the horizontal exterior finish plate 11 of the window frame, while vertical exterior finish plates 12 overlap and seal the vertical edges of the sash when closed, and 5 also serve with the plate 11 to limit its movement toward the exterior of the building, holding the sash nested snugly in position when closed.

The vertical movement of the sash permitted by my improved hinges is sufficient for the purposes in view, but said hinges 10 properly support the sash when the window is open and prevent it from being accidentally dismounted, as by wind or the efforts of a careless person in opening or closing the window.

It is evident from the foregoing that my invention provides a very advantageous casement window structure which possesses 20 all the advantages both practical and artistic of the casement type of window, and which is also weather-tight. It may be readily opened and closed, thus making ventilation and window cleaning easy. It is inexpensive, since it does not require complicated raising and lowering levers and supports, which are also unsightly. It does not interfere with flyscreens which need not be removed when the window is cleaned. When 30 the window is open, it is in its lowered position and cannot be closed until the sash is elevated to clear the bottom rail of the window frame. Therefore, the window cannot bang shut.

35 What I desire to claim is:—

1. In a casement window structure, the combination of a window frame having the inner surfaces of the top and bottom portions throughout their thickness downwardly and outwardly inclined, and an inwardly swinging sash adapted to occupy the opening in said frame and hinged to the frame along one of its vertical edges, in such a manner as to permit vertical movement of said sash relative to said frame, the upper and lower portions of the sash throughout their thickness having their outer surfaces inclined to mate with the inclines of said frame and said sash being 45 sufficiently shorter than said opening so that it may be elevated to clear said bottom surface in opening and closing, substantially as described.

2. In a casement window structure, the combination of a window frame provided with downwardly and outwardly inclined surfaces throughout the thickness of the frame at the top and bottom of the sash opening, an inwardly swinging sash adapted 55 to occupy said opening and hinged to the frame along one of its vertical edges, in such a manner as to permit vertical movement of said sash relative to said frame, the outer

surface of the upper and lower portions of the sash being inclined throughout the thickness of the sash to mate with the inclines of said frame and said sash being sufficiently shorter than said opening so that it may be elevated to clear said bottom surface in opening and closing, and an exterior closure 65 for the space existing between the top of the sash and the top of the sash opening when the sash is closed overlapping the upper portion of said opening from above.

3. In a casement window structure, the combination of a window frame provided throughout its thickness with downwardly and outwardly inclined surfaces at the top and bottom of the said opening, an inwardly swinging sash adapted to occupy said opening and hinged to the frame along one of its vertical edges in such a manner as to permit vertical movement of said sash relative to said frame, said sash being provided 75 throughout its thickness with top and bottom surfaces inclined to mate with the inclines of said frame and said sash being sufficiently shorter than said opening so that it may be elevated to clear said bottom surface in opening and closing, an exterior closure 80 for the space existing between the top of the sash and the top of the sash opening when the sash is closed overlapping the upper portion of said opening from above; and vertically disposed plates attached to the 85 sides of said frame and overlapping the sash opening to seal the vertical edges of the sash when closed.

4. In a casement window structure, the combination of a window frame provided throughout its thickness with a pair of parallel, opposed downwardly and outwardly inclined surfaces at the top and bottom of the sash opening and sealing members secured to the exterior surface of the frame at the top and sides of the sash opening of said frame and overlapping said sash opening, and an inwardly swinging sash of substantially the same thickness as the frame adapted to occupy said opening and hinged to the frame along one of its vertical edges in such a manner as to permit of vertical movement of the sash relative to the frame, said sash being provided throughout its thickness at its top and bottom with 105 inclined surfaces adapted to match with the surfaces of said frame and said sash being sufficiently shorter than said opening so that it may be elevated to clear the bottom surface and then permitted to slide outwardly and downwardly against and in sealing contact with said exterior sealing surfaces, substantially as and for the purposes described.

Signed at Pittsburgh, Pa. this 15th day of June, 1921.

GEORGIANNA W. DE WATERS.
